UNITED STATES PATENT OFFICE.

JULIUS PROEGER, OF PITTSBURG, PENNSYLVANIA, ASSIGNOR TO MCKEE & BROTHERS, OF SAME PLACE.

DESIGN FOR A COACH-BOWL.

SPECIFICATION forming part of Design No. 16,488, dated January 19, 1886.

Application filed December 4, 1885. Serial No. 184,746. Term of patent 7 years.

To all whom it may concern:

Be it known that I, JULIUS PROEGER, a citizen of the United States, residing at Pittsburg, in the county of Allegheny and State of Pennsylvania, have invented and produced a new and original Design of a Coach-Bowl; and I do hereby declare the following to be a full, clear, and exact description of the design, such as will enable others skilled in the art to which it appertains to make the same.

In the accompanying drawings, Figure 1 is a side, Fig. 2 a top, and Fig. 3 a bottom, view of my newly-designed bowl.

The leading features of my design are a bowl representing in form an ancient or open coach-body upon three imitation wheels, and the ornamentation of such body, in the manner shown in the drawings.

A is the bowl in form of an open coach-body having a slightly-flared shape from front to back, and provided with representations of a front central wheel, B, and two hind wheels, B' B'. The front wheel appears as if hung on a short axle, a, in a pendent hanger, a', and extending forward and upward from the hanger and front wheel is a rib, b, representing a draft-tongue, which terminates in a goose-neck, and within its curved portion is a prismatic ornament, b'. The hind wheels appear as if partly embedded in the sides of the bowl and hung on a connecting-axle, d, which is arched on its under side, united to the bottom of the bowl, and made to project a short distance downward from the outside surface of the said bottom, representing the hind axle for the two hind wheels of a coach-body. The inner surfaces of the bowl and wheels are plain or smooth, while their outer surfaces are roughened by ornamental prismatic projections. The upper edge of the coach-bowl is scalloped and shaped, as shown at e e', so as to present an ornamental appearance. On the outer sur-

face, all around the bowl, projecting panels f are formed, and between these panels are V-shaped channels f'. Each panel is provided with prismatic projecting ornaments of the different forms shown in the drawings. On the outer surface of the bottom of the bowl are ornaments g g', made up of prismatic projections of different forms, and arranged as shown in the drawings, and in rear and forward of these ornaments the remaining portions of the bottom are ornamented by projecting flutes, arranged as shown. The imitation wheels have broad treads or extension-rims, and appear as formed with radial spokes h h', which spokes are united by thin webs and ornamented by differently-shaped prismatic projections, as shown.

The effect of the design is handsome and novel.

What I claim is—

1. The within-described design for a bowl, comprising a representation of the open body of a coach with supports in imitation of wheels, as shown.

2. The design for a bowl, consisting of a representation of the open body of a coach with supports simulating wheels, together with the ornaments on the body and supports, as shown and described.

3. The design for a bowl, comprising a representation of the open body of a coach, simulated wheel-supports, draft-tongue, and ornaments representing scallops, panels, flutes, and prismatic depressions and projections, as shown and described.

In testimony whereof I affix my signature in presence of two witnesses.

JULIUS PROEGER.
